Primary Examiner — Susan Bennett Hattan*Assistant Examiner* — Rebecca Tsehay(74) *Attorney, Agent, or Firm* — Calfee Halter & Griswold LLP(57) **CLAIM**

We claim the ornamental design for a bottle, as shown and described.

DESCRIPTION

FIG. 1 is a top, perspective view of a bottle, showing the new design;

FIG. 2 is a bottom, perspective view of the bottle of FIG. 1; FIG. 3 is a front side view of the bottle of FIG. 1;

FIG. 4 is a left view of the bottle of FIG. 1;

FIG. 5 is a rear side view of the bottle of FIG. 1;

FIG. 6 is a right view of the bottle of FIG. 1;

FIG. 7 is a top view of the bottle of FIG. 1; and,

FIG. 8 is a bottom view of the bottle of FIG. 1.

The broken lines in the drawings showing the bottle illustrate the portions of the bottle that form no part of the claimed design.
